UNITED STATES PATENT OFFICE.

EVERETT T. SAMPSON, OF FRANKLIN, MASSACHUSETTS.

YARN CLAMP.

Application filed April 11, 1922. Serial No. 551,536.

To all whom it may concern:

Be it known that I, EVERETT T. SAMPSON, a citizen of the United States, and resident of Franklin, county of Norfolk, and State 5 of Massachusetts, have invented an Improvement in Yarn Clamps, of which the following description, in connection with the accompanying drawing, is a specification, like characters on the drawing representing like 10 parts.

This invention relates to a clamping device applicable for clamping or fastening warp yarn ends either to a warp beam of a loom or to the leader onto which the cloth 15 is wound as it is woven in the loom.

The common method now in vogue for attaching the warp yarns either to a warp beam or to the leader is to secure to the warp beam or leader a web of cloth which extends 20 the length thereof and to provide the edge of said web with eyelets or grommets into which yarn ends are tied. This method of fastening the warp yarns has the disadvantage that the operation of tying the warp 25 yarns into the eyelets or grommets is more or less laborious and it has the further disadvantage that frequently one or more of the knots will slip thus slackening up part of the warp threads.

The object of my present invention is to provide an improved clamping device by which the warp yarn ends may be securely fastened either to the warp beam or to the leader and which also has the advantage that 35 the operation of connecting the yarn ends to the clamping device requires less time than that of tying the yarn ends into the eyelets or grommets.

In order to give an understanding of my 40 invention I have illustrated in the drawings some selected embodiments thereof which will now be described, after which the novel features will be pointed out in the appended claims.

In the drawings:

Fig. 1 is a fragmentary view showing a portion of a warp beam equipped with my approved yarn clamping device;

Fig. 2 is an enlarged view of one of the 50 clamping devices;

Fig. 3 is an edge view showing the manner in which the yarn is clamped therein;

Fig. 4 is a perspective view illustrating the operation of the device;

Fig. 5 shows a modification.

In the drawings I have indicated at 1 a

warp beam of any suitable or usual construction such as is used in weaving operations. This warp beam has attached thereto a web or strip 3 of canvas or similar material as usual in warp beams.

4 indicates a web of warp threads, the ends of which are to be attached to the warp beam.

In the present invention this attachment is 65 made by means of a plurality of clamping devices embodying my invention. These clamping devices are indicated generally at 5 and each is formed with a hook-shaped portion 6 and with a yarn clamping member 7 which co-operates with the hook-shaped portion to grip the yarn ends. While the particular shape of the clamping member may be varied without departing from the invention, I have herein chosen to illustrate a clamping member having a body portion 8 which is formed at one end with the hook-shaped portion 6 and at the other end is provided with means for attaching it to the edge of the web 3. The means herein 75 shown is a loop or strap 9 which is secured to the edge of the web 3 and is looped through the slot 10 formed in the portion 11 extending laterally from the body 8.

The hook-shaped portion 6 is, preferably 85 provided with a concave inner yarn engaging face 12 and the clamping member 7 is pivotally connected to the body portion 8 and is of a length to overlie the beak or point 13 of the hook-shaped member. This 90 clamping member is herein shown as U-shaped. The body portion of the clamp is received between the ends 14 of the arms of the U-shaped clamping member and said ends are pivotally connected to the body 95 portion by the pivot 15. The clamping member is of sufficient length to extend over the beak or point 13 of the hook and when the parts are in operative position said beak enters between the two sides of the yarn 100 clamping member as clearly seen in the drawings.

The yarn clamping member is also preferably formed on its inner face with a concave yarn receiving edge 16.

In connecting the yarn to the clamping devices the web of warp will be divided into separate bunches or groups 17, one for each clamping device, and in connecting any bunch of yarn to the clamping device said 110 yarn will be above the clamping device and will then be introduced into the space be-

hind the clamping member 7 and between the latter and the portion 8, and then the clamping member will be swung into the dotted line position Fig. 2 and the end of the bunch 5 will be passed around the clamping member and between the latter and the point 13 of the hook. The operator then draws on the ends of each bunch to tighten the warp threads and this results in drawing the bunch 10 of warp threads around the clamping member 7. As the warp yarns are drawn taut the tension thereof will cause the clamping member 7 to swing toward the clamping edge 12 thereby gripping the bunch firmly 15 between the straight face 18 of the clamping member and the curved face 12 of the hook-shaped portions 6. Owing to the fact that the clamping member 7 is pivotally connected to the body 8 all the strain on the yarn will 20 tend to draw the clamping member 7 toward the clamping edge 12 and therefore the grip which the clamping member has on the yarn will be proportional to the strain on the yarn. When the member 7 is in clamping 25 position the beak 13 of the hook-shaped member is located between the two sides of the clamping member and said beak thereafter serves to hold the clamping member in proper position.

30 I will preferably provide a sliding pivotal connection between the clamping member and the body 8 by forming the latter with a slot 19 into which the pivot pin 15 operates. The advantage of this construction is that 35 the clamping member may move bodily toward and from the clamping edge 12 thereby to accommodate different sized bunches of yarn.

The body portion 8 will preferably be 40 made slightly curved as shown in Fig. 3, so that it will fit the curvature of the warp beam 1 which is indicated in dotted lines of Fig. 3. With this construction the clamping device will lie flatly on the curved surface of the warp beam and will take up no 45 more room than that occupied by the knots where the warp threads are tied into the web 3.

If desired I may make the body 8 in two 50 sections 20 and 21 which are hinged together as shown at 22 in order to provide a flexible clamping member which will readily fit warp beams of different diameters.

55 My improved clamping device is easy to manipulate and it is certain in its action because when the warp ends are once clamped therein there is no possibility that they will slip. As a result an even tension of all the warps is ensured.

60 While I have illustrated some selected embodiments of my invention I do not wish to be limited to the constructional features shown.

65 While I have referred to the beam 1 as a warp beam yet I wish it understood that the

invention is not limited in its application to a warp beam but is capable of use for connecting the yarn ends to the leader or any other similar roll and, therefore, the term "warp beam" as used in the specification and claims is not intended to import any limitation.

I claim:

1. The combination with a warp beam having a web of cloth attached thereto, of a plurality of warp-yarn clamping devices secured to the edge of said web, each clamping device comprising a flat body member having a hook-shaped portion and a yarn-clamping member connected to the body member for both bodily and swinging movement toward and from the hook, the end of the yarn-clamping member being adapted to overlie the point of the hook, whereby when 75 yarn ends are carried around the clamping member and then between the latter and the inner edge of the hook the tension to which the yarn is subjected will cause the clamping member to clamp the yarn against the inner edge of the hook.

2. A yarn-clamping device for connecting warp-yarn ends to a beam and comprising a flat body member having a hook-shaped portion, means connected to the opposite end of said member for attaching it to the beam, a yarn-clamping member connected to the body so that it can move bodily and also swing toward and from the hook, the end of said yarn-clamping member adapted to overlie the point of the hook whereby when 90 yarn ends are carried around the clamping member and then between the latter and the inner edge of the hook the tension to which the yarn is subjected will cause the clamping member to clamp the yarn against the inner edge of the hook.

95 3. The combination with a warp beam, of a plurality of yarn-clamping devices secured thereto, each clamping device comprising a flat body member having a laterally-extending portion at one end formed on its inner edge with a yarn-receiving recess, a clamping member pivotally connected to the body adjacent one side of the recess, the end of the clamping member adapted to overlie the end of the lateral portion at the opposite side of the recess, said clamping member having a 100 yarn-clamping edge facing the recess and having sufficient swinging movement so that when a bunch of yarn is passed around said 105 yarn-clamping member and then between said yarn-clamping edge and the wall of the recess the tension to which the yarn is subjected will cause the yarn-clamping member to clamp the yarn against the wall of the recess.

110 4. A yarn-clamping device for connecting warp yarn to a beam comprising a C-shaped articulated member, means connected with one arm of said member for attaching it to 115

120

125

130

a warp beam, the other arm of said member having a yarn-receiving recess, and a yarn-clamping member pivoted to the C-shaped member and having a yarn-clamping edge, whereby when a bunch of yarn is passed around the yarn-clamping member and into the recess the tension to which the yarn is

subjected will cause the yarn-clamping member to clamp the yarn between the yarn-clamping edge and the wall of the recess. 10

In testimony whereof, I have signed my name to this specification.

EVERETT T. SAMPSON.
